UNITED STATES PATENT OFFICE.

GEORGE S. WELLS AND HERBERT P. EWELL, OF ROCHESTER, MICHIGAN;
SAID WELLS ASSIGNOR TO SAID EWELL.

TRUSS.

SPECIFICATION forming part of Letters Patent No. 435,910, dated September 2, 1890.

Application filed November 23, 1889. Serial No. 331,341. (No model.)

To all whom it may concern:

Be it known that we, GEORGE S. WELLS and HERBERT P. EWELL, both citizens of the United States, residing at Rochester, county 5 of Oakland, State of Michigan, have invented a certain new and useful Improvement in Hernial Trusses; and we declare the following to be a full, clear, and exact description of the same, such as will enable others skilled in 10 the art to which it pertains to make and use the same, reference being had to the accompanying drawings, which form a part of this specification.

In the drawings, Figure 1 is a perspective 15 view of a truss embodying our invention. Fig. 2 is a plan view of the same. Fig. 3 is a longitudinal sectional view of the same. Fig. 4 shows the same as adapted for a single pad.

It is the purpose of our invention to provide 20 a truss-pad with a projection adapted to extend upward or downward along the groin to steady the pad and hold it in the proper position; also, to provide a truss-pad with a spring, the pressure of which against the body 25 is due directly to the strain on the strap, which passes around the body of the wearer.

In carrying out our invention, A represents 30 the uniting bars or wires of a double hernial truss.

B is a set-screw, by which each pad may be slightly adjusted to and fastened at any position on its supporting-bed.

C represents the pads. We prefer that the pads shall be of metal, although they may be 35 of wood or rubber or other suitable material. They are held in place by the set-screws B, which serve also as binding-screws for this purpose.

D represents a spring, preferably of brass 40 or bronze wire, bent into substantially the form shown, and forming at their outer or free ends loops d for the ends of the body-strap E. In the double truss one end of the strap engages one of these springs and the 45 other end of the strap engages the spring on the other pad. If it is employed in the form of a single-pad truss, the strap would have one of its ends attached to the loop of the spring and the other to the loop F, as shown in Fig. 4.

G represents loops from which straps pass 50 down beneath the body to assist in holding the pad or pads in place.

We usually make the device, as shown in Fig. 3, with the wires or bars A projecting at one end beyond the adjacent pad. This is to 55 facilitate its adjustment to the body of any wearer. When the pads are properly set, the projecting ends may be cut off and the ends riveted in place; or the pad-supports might be made adjustable along these frames and 60 be set therein in any desired position of adjustment. It will be observed that the springs D are removable, so that should any spring be of too great or too little tension it might be removed and one having a proper tension substituted in its place. 65

The pads C may be of any ordinary form; but we prefer that they shall have hollow projections C', adapted to extend upward or downward along the groin to aid in holding 70 the pad in its proper place with respect to the hernia to be treated and to prevent its becoming displaced. This structure is at once light, cleanly, and adjustable to meet the requirements of any particular patient. 75

So far as the truss pad and spring are concerned, we would have it understood that our invention is not limited to hernial trusses, but is equally applicable to trusses adapted for the treatment of other ruptures, or where 80 similar treatment is required.

What we claim is—

1. A truss-pad provided with a semi-elliptic spring adapted at its free end for the reception of one end of the body-strap, substantially as and for the purposes described. 85

2. A double truss consisting of supporting bars or wires A, and truss-pads located thereon, each truss-pad provided with a spring D, the body-strap having one of its ends fastened 90 to the free end of one of said springs and its other end attached to the free end of the other spring, substantially as and for the purposes described.

In testimony whereof we sign this specification in the presence of two witnesses. 95

GEORGE S. WELLS.
HERBERT P. EWELL.
